UNITED STATES PATENT OFFICE.

ARTHUR F. ROSE, OF WEST BRIGHTON, NEW YORK, ASSIGNOR TO AMERICAN TELEPHONE AND TELEGRAPH COMPANY, A CORPORATION OF NEW YORK.

TELEPHONE REPEATER SYSTEM.

Application filed March 24, 1921. Serial No. 455,236.

The principal object of my invention is to provide a new and improved repeater system adapted for operation between lines of different characteristic impedance. Another 5 object of my invention is to provide a repeater with a single repeating element or series of repeating elements to operate between two lines, each balanced by a respective artificial line. These objects and other 10 objects of my invention will become apparent upon consideration of a specific embodiment of the invention, which I will now proceed to disclose, with the understanding that the invention is defined in the appended claims.

15 The accompanying drawing is a diagram showing my improved repeater system, in connection with a loaded line and a smooth line, by way of example.

20 The transmission lines 11 and 13 between which it is desired to repeat, may be any two lines having the same characteristic impedance or different characteristic impedances. I have shown the line 11 as a loaded line with the loading coils 12 and with any 25 convenient termination which may be at part-section or at part-load. The line 13 is shown as a smooth line. The network 22 is designed accurately to balance the line 11 and the network 22' provides a similar 30 balance for the line 13. The usual hybrid coil transformer 14—16 is provided between the line 11 and the network 22. At the middle points 15 of the coils 14, the conductors 17 carry the input to the repeater element 19. Similarly, from the hybrid coils associated with the line 13, the conductors 17' bring the input, both the conductors 17 and 35 17' being united at 18 to carry the input currents to the element 19.

40 The output currents from the repeater element 19 go through a wave filter 20, whose function will be explained presently, whence the branch conductors 21 and 21' go respectively to the coils 16 and 16' in inductive 45 relation with the series coils 14 and 14'.

45 The useful frequency range may be less than the entire frequency range below the critical frequency for the loaded line 11, and it may be desirable to make the network 50 22 balance the line 11 over only the useful frequency range. Accordingly, the low-pass wave filter 20 is provided, having its critical frequency corresponding to the upper limit of the useful frequency range, so

that other frequencies shall not be put on the 55 line from the repeater element 19.

Assuming that voice currents come in from the left over the line 11, they will flow in considerable proportion through the branch conductors 17 and again in considerable 60 proportion through the conductors 18 to the input side of the repeater element 19. The amplified currents from the repeater element 19 will be restricted to the useful frequency range by the wave filter 20. These 65 output currents, after passing through the filter 20, will divide to the branch conductors 21 and 21'. The currents in the conductors 21' and the coil 16' will induce currents in the coils 14', the energy of which 70 will divide equally to the line 13 and the artificial line 22'.

Thus the current output from the filter 20 will be divided twice, so that only a quarter of the energy-output from the filter 20 will 75 be put on the line 13. However, it is easy to amplify to the necessary extent, and the repeater element 19 may comprise more than one amplifying element in tandem relation, if so desired.

80 On account of the location of the points 15' midway in the divided coil 14' and because of the balance between the artificial line 22' and the line 13, none of the output energy received through the branch conductors 21' and coil 16' will be put in the conductors 17'. This is an important consideration because if any of the output energy 85 passes to the input, "singing" may result, with obvious impairment of the service. 90

Just as the output energy going over the conductors 21' is balanced out as to its effect on the input circuit 17', so the output through 21 is balanced in its effect on the input conductors 17.

95 I claim:

1. In combination, two transmission lines, each balanced by a respective network, with a respective hybrid coil between each said line and its network, a single repeater element and input connections thereto from both said coils and output connections therefrom to both said coils.

100 2. In combination, two lines with which it is desired to repeat signaling currents from either to the other with amplification thereof, two networks, each in equal balanced relation with a respective line independently

of the remaining line and network, a common amplifying element, means to carry the inputs from both lines to said element, and means to divide the output therefrom to both said lines.

3. In combination, two lines of different characteristic impedance, two networks, each in equal balanced relation with a respective line independently of the remaining line and network, and a single repeater element with like input connections from both lines and like output connections to both lines.

4. In combination, two dissimilar lines, respective networks balancing said lines, respective hybrid coil transformers between each line and its network, a repeater element connected on its input side alike with said transformers, a wave filter connected to the output side of the said repeater element and like connections from said filter to said transformers.

5. In combination, two transmission lines,

two networks, each in equal balanced relation with a respective line independently of the remaining line and network, and a single ²³ repeater element with its input connected alike with both said lines and with its output connected alike with both said lines.

6. In combination, two transmission lines, each balanced by a respective network, with ³⁰ a respective hybrid coil between each said line and its network, a single repeater element having a pair of input conductors and a pair of output conductors, the said input conductors being connected in multiple and ³⁵ alike with the two lines and the said output conductors also being connected in multiple and alike with said lines and so that the output currents are of no effect on the said input conductors.

In testimony whereof, I have signed my name to this specification this 17th day of March, 1921.

ARTHUR F. ROSE.
